(57) CLAIM

We claim the ornamental design for the cork holder, as shown and described.

DESCRIPTION

FIG. 1 is a perspective view of a cork holder embodying the invention;

FIG. 2 is a front view of the cork holder of FIG. 1; and,

FIG. 3 is a bottom view of the cork holder of FIG. 1.
